UNITED STATES PATENT OFFICE

2,656,739

METHOD OF FORGING A HEADED ELEMENT

Judson H. Mansfield, Rockford, Ill., assignor to
 Greenlee Bros. & Co., Rockford, Ill., a corpora-
 tion of Illinois

Application October 6, 1950, Serial No. 188,822

2 Claims. (Cl. 76—101)

1

This invention relates to headed elements of the type from which tools such as wood bits are made having a pyramidal shape to interfit with the jaws of a drill chuck or the like. Such tool heads or so-called bit squares have heretofore been formed by hot forging which requires extreme skill on the part of the operator in order to form the sides of the pyramid with square corners and necessitates subsequent machining of the surfaces.

The primary object of the present invention is to provide a novel head construction of the above character which permits the latter to be formed by cold forging without any subsequent machining.

Another object is to shape the flat sides and the base of the pyramid in a novel manner such that the sides may be formed by lateral compression of a conical frustum.

The invention also resides in the novel method of and the die for shaping the pyramidal heads.

Other objects and advantages of the invention will become apparent from the following detailed description taken in connection with the accompanying drawings, in which:

Figures 1 to 3 are elevational views illustrating the successive steps in the formation of the improved tool head.

Figs. 4 and 5 are cross sections taken respectively along the lines 4—4 and 5—5 of Figs. 2 and 3.

Fig. 6 is an enlarged elevational view of the finished tool head.

Fig. 7 is an end view.

Fig. 8 is a fragmentary elevational view of the die arrangement used in the final shaping of the tool head.

Figs. 9 and 10 are fragmentary sectional views taken along the line 10—10 of Fig. 8 and showing the die elements in open and closed positions respectively.

Fig. 11 is a fragmentary section taken along the line 11—11 of Fig. 10.

Fig. 12 is an enlarged view of a part of Fig. 11.

While the invention is susceptible of various modifications and alternative constructions and may be practiced in various ways, I have illustrated in the drawings and will herein describe the preferred embodiment and manner of carrying out the invention. It is to be understood that I do not thereby intend to limit the invention by such disclosure but aim to cover all modifications, alternative constructions, and methods, falling within the spirit and scope of the invention as expressed in the appended claims.

2

The improved tool head indicated generally at 10 is upset on one end of a cylindrical blank 11 (Fig. 1) one portion 12 of which constitutes the shank of the tool. The head 10 is of generally pyramidal shape dimensioned to correspond to the hot forged bit squares of standard construction and having four flat side faces 13 which converge axially and intersect a convexly rounded end surface 14 along arcs 18. At the base of the pyramid, the wider ends of the side faces 13 intersect and interrupt a frusto-conical surface 15 along an arcuate line 16 whose center terminates near the apex end of the conical surface which intersects the shank 12 around a circular line 17.

To facilitate final shaping of the head by cold forging, the adjacent edges 20 of the flat faces 13 are separated from each along the full length of the faces between the arcs 16 and 18 of intersection with the end surfaces 14 and 15 and are connected by narrow facets 21 which form the corners of the pyramid. These facets are of substantially uniform and equal widths throughout their lengths and are slightly rounded in cross section so as to impart a slightly beveled appearance to the corners of the head. At their opposite ends, the edges of the facets merge with the ends of the intersection arcs 16 and 18.

The head 10 of the contour described above is formed in one or more heading operations followed by a final cold forging in a separate special die assembly. Preferably, the preliminary heading is accomplished in one step and entirely automatically in a heading machine of well known construction such as are used in forming the heads of screws and bolts. In the die of the heading machine, the metal at the exposed end of the blank 11 is upset and simultaneously shaped to form a head 23 of the contour and the dimensions shown in Fig. 2. The head comprises an elongated cone 28 merging at its smaller end with a rounded end surface 22 and at the other end intersecting a shorter and inverted conical frustum 25 of a height equal to that of the surface 15 in the final head. The cone 28 is shaped with a non-uniform taper the angle of which decreases progressively from a common line 26 substantially to zero at 27 where the surface merges with the rounded end 22 of the blank. The contour of the surface 23 is important in controlling the proper flow of metal in the final forging step and is determined by a cut and try process for different sizes and shapes of the head 10.

55 The shaping of the head to the desired pyram-

idal shape is effected by compressing the entire length of the conical part 28 and the major base portion of the head 23 radially between four rigid flat die surfaces 29 preferably having side edges 30 converging upwardly toward each other in the direction of the taper 28 with the edges of the adjacent surfaces disposed parallel to each other and laterally spaced apart short distances in the final collapsed position of the die as shown in Fig. 12. These surfaces are on the inner sides of heavy metal blocks 31 which are mounted in a hollow die frame 32 to swing in radial planes 33 and 34 (Fig. 11) disposed perpendicular to each other. The blocks are of triangular horizontal cross section as shown in Fig. 11 and at their upper ends bear against the exterior of a ball 53 which is seated in a cup-shaped head 49 and defines at its center the fulcrum about which the four die blocks 31 swing. The upper block ends are exteriorly confined at 35 by vertical surfaces 36 on the head 49 which is slidable in a vertical guideway 50 within the die frame 32 and is urged downwardly relative to the latter by compression springs 51. Lugs 37 on the upper ends of the blocks 31 bear against a downwardly facing surface 38 on the slidable head 49, the faces of the lugs coming into full contact with this surface when the blocks are swung together as shown in Figs. 10 and 11. A plunger urged downwardly by a spring 39 acts on cam surfaces 40 to urge the blocks 31 apart.

In the present instance, the pressure for swinging the lower ends of the blocks together with sufficient force to forge the upset head into the desired shape is derived by the action of toggle links 41 fulcrumed at their outer ends on pins 42 rigidly supported in the die frame. At their inner ends, each link is curved to fit around an arcuate surface 43 on the lower end portion of the associated block. Thus, when the die frame 32 is forced downwardly from the open position shown in Fig. 9, the two pairs of toggle links are straightened forcing the blocks 31 inwardly about the center of the ball 53 as a fulcrum to the limit position shown in Figs. 10 and 11, these positions being determined accurately by engagement of a bottom plate 44 on the die frame with the top of the fixture base 45. A boss 46 upstanding from the latter is adapted to pass through an aperture in the bottom plate 44 and is recessed to receive the shank 12 of the upset blank. At its upper end, the boss 46 is formed with a flat surface 47 on which the lower arcuate ends 48 of the blocks 31 slide as the blocks are swung inwardly by the action of the toggles 41.

In operation, the shank of the work blank is inserted in a hole in the boss 46 while the die frame 32 is raised as shown in Fig. 8; the upset head on the blank thus being aligned with the downwardly flaring opening defined by the surfaces 29 of the die blocks 31. At this time, the latter are spread apart as shown in Fig. 9 by the action of the springs 51 which force the slidable head 49 downwardly and flex the toggle links 41, this movement being limited by engagement of the lower ends 48 of the die blocks with the bottom plate 44 of the die frame 32.

The forging operation is effected by moving the die supporting frame 32 downwardly to the limit determined by engagement of the bottom plate 44 with the top of the fixture base 45. As the die frame approaches this position, the boss 46 enters the hole in the bottom plate and the arcuate surfaces 48 thereon engage the die block surfaces 47 thus interrupting the downward

movement of the die blocks. At this time, the parts will be positioned as shown in Fig. 9, the upset head of the work blank being disposed within the die surfaces 29 substantially at the level of the inner toggle pivots 43.

Now, as the die frame continues its downward movement, the outer pivots 42 of the toggles move downwardly while the inner pivots and the die blocks remain fixed vertically. This results in straightening the toggles and as a consequence forcing the die blocks 31 inwardly, the lower ends 48 riding along the surface 47 of the fixture. The four die faces 29 first engage the blank head at opposite ends of the elongated conical surface 28 and at points angularly spaced around the latter. As the compression of the head continues, the displaced metal flows upwardly only by virtue of the particular contour of the surface 28 and the head of the blank is elongated upwardly but only above the junction line 26.

By the time that the die frame reaches its limit downward position against the top of the fixture base 45 as shown in Fig. 11, the sides of the die blocks 31 will have come into close proximity as shown in Figs. 11 and 12, and the edges 30 of the adjacent die faces 29 will be disposed close together, about .010 of an inch, but nevertheless spaced apart. This allows the displaced metal to flow outwardly but such flow is small and, with the blank head contoured as described above, takes place uniformly along the openings between the blocks in spite of the upward displacement of the metal and elongation of the head. As a result of this natural metal flow, the facets 21 between the flat sides 13 of the pyramid are formed to a slightly rounded contour and curve gradually along their edges into coincidence with the plane of the surfaces 13. Thus, the facets are of substantially uniform width throughout their length even though they are not actually shaped by a die surface.

When the die head is again raised, the springs 51 will hold the die blocks 31 downwardly against the fixture base 46 until the bottom plate 44 engages the block ends 48. In this relative movement between the die frame and the blocks, the toggles are flexed permitting the blocks to be spread apart by the action of the spring 39. The head 19 thus finished on the work blank is released from the die and the blank may be withdrawn from the fixture after further upward retraction of the die frame.

I claim as my invention:

1. The method of cold forging a head of pyramidal shape on one end of a cylindrical bar which comprises rounding the bar end and upsetting the adjacent portion of the bar to form an outwardly flaring frusto-conical surface and a longer conical surface of decreasing taper and concave cross section converging from the base of said first surface into tangency with said rounded bar end, positioning the partially formed head between four rigid flat die surfaces converging along said second conical surface substantially equidistantly therefrom and each having straight side edges converging in the direction of taper of the second surface, and forcing said die surfaces radially toward each other to compress the entire length of said second conical surface and the adjacent base portion of said first conical surface inwardly until the side edges of said die surfaces are disposed adjacent but laterally spaced from each other whereby the natural flow of metal forms a narrow facet at each corner of the resulting pyramid;

2. The method of cold forging a head of pyramidal shape on a cylindrical metal bar which comprises upsetting one end portion of the bar to form a rounded end, a frusto-conical surface spaced from and flaring outwardly toward such end, and a longer conical intermediate surface of shorter axial length than said pyramidal head converging gradually from intersection with the base of said first surface into emergence with the surface of said rounded end, positioning the partially formed head between four rigid flat die surfaces converging along said intermediate surface substantially equidistantly therefrom and each having straight side edges converging in the direction of the taper of said intermediate surface, and forcing said die surfaces radially toward each other to compress the entire length of the intermediate conical portion and the adjacent base portion of the first conical portion inwardly until said side edges of the die surfaces are disposed adjacent but laterally spaced from

each other whereby to elongate said intermediate portion into said pyramidal head and, by the natural flow of metal, form a narrow unforged facet of substantially uniform width at each corner of the pyramid.

JUDSON H. MANSFIELD.
